US00D816142S

(12) **United States Design Patent** (10) **Patent No.:** **US D816,142 S**
(45) **Date of Patent:** **** Apr. 24, 2018**

(54) **CAMERA**

(71) Applicant: **Xiaoyi Technology Co., Ltd.**, Pudong New Area, Shanghai (CN)

(72) Inventor: **Ye Song**, Shanghai, CA (US)

(73) Assignee: **SHANGHAI XIAOYI TECHNOLOGY CO., LTD.**, Shanghai (CN)

(**) Term: **15 Years**

(21) Appl. No.: **29/561,182**

(22) Filed: **Apr. 14, 2016**

(51) LOC (11) Cl. **16-01**

(52) U.S. Cl.

USPC **D16/203**

(57) **CLAIM**

The ornamental design for a camera, as shown and described.

DESCRIPTION

FIG. 1 is a top, front, right perspective view of a camera showing my new design;

FIG. 2 is a front elevation view thereof;

FIG. 3 is rear elevation view thereof;

FIG. 4 is a top plan view thereof;

FIG. 5 is a bottom plan view thereof;

FIG. 6 is a left elevation view thereof; and,

FIG. 7 is a right elevation view thereof.

The broken lines in the drawings depict portions of the camera that form no part of the claimed design.

1 Claim, 7 Drawing Sheets
